DETACHABLE RUBBER HEEL

Filed Dec. 27, 1920

Inventor:
William A. Maloney.
By Southgate & Southgate
Attorneys.

UNITED STATES PATENT OFFICE.

WILLIAM A. MALONEY, OF NEWTON, MASSACHUSETTS.

DETACHABLE RUBBER HEEL.

Application filed December 27, 1920. Serial No. 383,195.

To all whom it may concern:

Be it known that I, WILLIAM A. MALONEY, a citizen of the United States, residing at Newton, in the county of Middlesex and State of Massachusetts, have invented a new and useful Detachable Rubber Heel, of which the following is a specification.

This invention relates to a rubber heel adapted to be detachably secured to a shoe. 19 It is highly desirable that such a heel shall fit closely against the shoe around the edges thereof and that the parts shall continuously maintain close contact.

It is an important object of my invention 15 to provide means by which close and permanent contact may be maintained between the heel and the shoe so long as the heel remains in use.

With this general object in view my invention in its preferred form contemplates 20 the provision of a stiff wire or rod embedded in the heel and extending continuously adjacent the sides and curved rear wall of the heel.

25 I further provide an attaching device extending beneath the wire or rod at each side of the heel by which means a direct upward pull is communicated to the heel near the edge thereof, thus holding the parts firmly in contact.

My invention further relates to arrangements and combinations of parts which will be hereinafter described and more particularly pointed out in the appended claim.

25 A preferred form of my invention is shown in the drawings in which—

Fig. 1 is a longitudinal sectional view of my improved heel attached to a shoe;

Fig. 2 is a bottom view of the heel lift 40 which is permanently secured to the shoe;

Fig. 3 is a plan view of the detachable heel;

Fig. 4 is a sectional view of the heel lift, on the line 4—4 in Fig. 2;

Fig. 5 is a sectional view of the detachable heel on the line 5—5 in Fig. 3; and

Figs. 6, 7 and 8 are perspective views of detail parts to be described.

Referring to the drawings, my improved heel construction comprises a heel lift 10 permanently secured to the shoe 11 and a detachable heel 12 commonly formed as a single block of molded rubber. Projections 13 on one of the parts fit closely in recesses 14 in the other part, thus preventing relative angular movement of the parts.

In the manufacture of the detachable heel 12 I place a wire or rod 15 in the mold so that it is entirely embedded in the rubber and extends continuously along the sides and rear portion of the heel, adjacent the outer surface thereof but spaced slightly inwardly therefrom.

I also provide a metal plate 16 extending transversely of the heel and having its outer ends disposed beneath the wire 15. The outer ends of the plate are preferably notched or shouldered as shown in Fig. 8 and the shoulders engage the wire 15, thus preventing relative transverse movement between the plate and the heel. The plate 16 is provided near its center with an upwardly enlarged projection 17 by which the heel is secured to the shoe.

Any suitable fastening or locking means 75 may be provided for thus securing the heel to the shoe, such, for instance, as are disclosed in my pending application, Serial No. 383,668, filed May 24, 1920.

These fastening devices are shown in Figs. 80 2, 6 and 7, said devices comprising a locking plate 18 mounted to slide lengthwise of the shoe and a holder 19 for said plate embedded in the heel lift 10. The holder 19 has a slot 20 and the locking plate 18 has a slot 21 enlarged at its rear end.

In assembling the parts the projections 13 are inserted in the recesses 14 and the projection 17 is inserted through the slots 20 and 21, the locking plate being in its forward position as shown in dotted lines in Fig. 1. The plate 18 is then pushed rearward, bringing the projection 17 into the narrow portion of the slot 21 and holding the parts firmly in position.

As any tension on the projection 17 is transferred through the plate 16 to the wire 15, it will be seen that the upward pull of the locking plate is communicated to the outer edges of the heel, thus holding the outer portions of the heel in close contact with the heel lift attached to the shoe.

Having thus described my invention, it will be evident that changes and modifications can be made therein by those skilled in the art within the spirit and scope of my invention as set forth in the claim and I do not wish to be otherwise limited to the details herein disclosed but what I claim is:

A rubber shoe-heel comprising a detachable rubber heel, a curved wire embedded in said rubber heel and extending continuously

adjacent the sides and rear curved surface of said heel, and means to secure said heel to the shoe, said means comprising a rigid metal plate extending transversely of said heel and embedded therein with its sides perpendicular to the lower face of said heel and with its ends formed with shoulders and reduced extensions both engaging said wire on the lower and inner 10 sides of said wire, said plate being also pro-

vided with an upwardly enlarged integral projection at the middle portion of its upper edge and said shoe having a co-operating locking device fastened thereto whereby the edges of said rubber heel are positively forced into firm engagement with the bottom of the shoe. 15

In testimony whereof I have hereunto affixed my signature.

WILLIAM A. MALONEY.
